(57) **CLAIM**

The ornamental design for an applicator for lip cosmetics, as shown and described.

DESCRIPTION

FIG. 1 is a front elevational view of an applicator for lip cosmetics, showing my new design;

FIG. 2 is a rear elevational view thereof;

FIG. 3 is a side elevational view thereof from the left of FIG. 1, the appearance of the side opposite that shown in FIG. 3 being identical thereto;

FIG. 4 is a top plan view thereof;

FIG. 5 is a bottom plan view thereof; and,

FIG. 6 is a top and side perspective view thereof.

The material shown in broken lines forms no part of the claimed design.
